UNITED STATES PATENT OFFICE

LAURENCE S. HARRISON, OF NEW YORK, N. Y., ASSIGNOR TO INTERNATIONAL TIME RECORDING COMPANY OF NEW YORK, OF ENDICOTT, NEW YORK, A CORPORATION OF NEW YORK

SYNCHRONIZING CLOCK SYSTEM

Application filed November 29, 1924. Serial No. 753,008.

My invention relates to clock systems, and it has particular relation to such systems as may be energized from alternating-current sources.

5 One object of my invention is to provide an alternating-current clock system which shall not only reset automatically but which shall also be self-synchronizing.

Another object of my invention is to provide 10 a synchronizing clock system, wherein an increased alternating-current voltage is employed to accelerate and reset all secondary clocks after a failure of the source of energy.

A further object of my invention is to provide 15 a synchronizing clock system, wherein a single conductor common to all the secondary clocks furnishes synchronizing currents at regular intervals to correct such secondary clocks as may have departed from 20 synchronism with a main synchronizing clock.

A still further object of my invention is to provide a secondary clock mechanism which shall be accelerated if slow and retarded if 25 fast by the respective reversals of electric currents through a regulating coil.

A still further object of my invention is to provide a secondary clock movement having a time rate which may be varied by adjusting 30 the position of a permanent magnet with respect to a rotating member such as constitutes the actuating disk of an alternating-current watt-hour meter.

With these and other objects and applications in mind, my invention further consists 35 in the details of construction and operation and circuit arrangement, hereinafter set forth in the accompanying description, claims and drawings, wherein,

40 Fig. 1 is a diagrammatic view of an alternating-current, automatic resetting, self-synchronizing clock system embodying my invention;

Fig. 2 is a perspective view of the actuating motor for the main synchronizing and secondary clocks;

Fig. 3 is an enlarged detail perspective view of the structure of Fig. 2, showing the minute shaft and associated switch mechanism;

50 Fig. 4 is a similar view of the mechanism

interconnecting the main synchronizing clock and the master clock as well as certain switches actuated thereby;

Fig. 5 is a perspective view of the structure of Fig. 4 viewed from the right; and

Fig. 6 is a sequence chart illustrating the operating periods of the secondary and main-synchronizing clock control-switches.

In the illustrated form of my invention shown in Fig. 1 of the drawing, a source of alternating-current energy (not shown) is connected by conductors 1 and 2 to the opposite terminals 3 and 4, respectively, of an auto-transformer 5 having an adjustable intermediate tap connection 6. A main power circuit 7 for a main synchronizing clock 8 and a plurality of secondary clocks 9, comprises a conductor 11, which extends from the terminal 3 of the auto-transformer 5, and a conductor 12. The conductor 12 may be connected either to the intermediate tap connection 6 or to the terminal connection 4 of the auto-transformer 5 through mechanically connected switches 13 and 14 and conductors 15 and 16, respectively.

My invention contemplates an actuating motor 17 for each of the secondary clocks 9 and the main synchronizing clock 8 of the construction shown in Fig. 2, wherein a potential coil 18 and a regulating coil 19 are mounted on a laminated core 21 in such manner as to establish magnetic fluxes which at any given instant are approximately ninety electrical degrees out of phase. The coils 18 and 19 are spaced sufficiently to provide an air gap 22, wherein a disk 23 may be positioned. The disk 23 is revolubly mounted on a vertical shaft 24 and it is connected to the usual clock gear train 25 of which only a worm-and-wheel are shown. The disk 23 is so positioned with respect to the windings 18 and 19 that eddy currents are induced therein with the result that a torque is established tending to rotate the disk 23.

A resistor 26 and a second regulating coil 95 27 may also be mounted on the core 21. As shown in Fig. 1, the terminals of the potential coil 18 are connected by conductors 28 and 29 to the terminals of the regulating coil 19, whereby the same may be connected in 100

multiple-circuit relation, and the resistor 26 is inserted in the conductor 28.

The electrical constants of the coils 18 and 19 are such that the disk 23 operates at the rate of five to ten revolutions per minute, corresponding to normal clock time rate. The disk 23 may rotate before a small aperture (not shown), whereby the clock time rate may be easily checked by noting the passage of a marker 31 across the aperture.

The rate of rotation of the disk 23 may be controlled by means of a damping magnet 32, the poles 33 of which may be adjusted radially over the disk 23 and secured in any desired position. The terminals of the potential coil 18 may be connected by conductors 34 and 35 to the conductors 12 and 11, respectively, of the main power circuit 7.

Should there be an interruption in the current supply to the transformer 5 or should the voltage or frequency of the alternating currents vary, resulting in a departure of the secondary clocks 9 and the main synchronizing clock 8 from their normal time rate, my invention embodies means for automatically advancing, at a relatively high rate, upon a resumption of normal current flow, the hands of the secondary and main synchronizing clocks to normal or correct time position. To this end, I provide a cooperating master clock 36, a driven shaft 37 of which is journaled on a frame 38.

A member 39 which is rigidly secured to a master clock shaft 37, is provided on one face 41 (Fig. 5) with an insulating sleeve 42 having collector rings 43 and 44, the latter serving to connect electrically relatively movable contact members 45 and 46 to stationary brushes (not shown). The contact member 45 is rigidly secured to face 41 of the member 39 near the outer periphery thereof. The co-acting movable contact member 46 is positioned on one end of an arm 47 which is pivotally mounted on a pin 48 extending from the face 41. A spring 49 cooperating with the operating arm 47 causes a quick make-and-break between the co-acting contact members 45 and 46. The arm 47 may be provided with a slot 51 adapted to receive one end 52 of a pin 53, an opposite end 54 of which extends through a slot 55 in the member 39 and is rigidly secured to an arm 56 pivoted at 57. A spring 58 tends to cause an end portion 59 to engage an abutment 61, in which position the contact members 45 and 46 are disengaged, (Figs. 4 and 5). When the arm 56 is moved from the position shown in Fig. 4, the movable contact member 46 is actuated into engagement with the contact member 45 against the force of the spring 58.

In order to cause the opening of the contact members 45 and 46 when the main synchronizing clock 8 departs from synchronism with the master clock 36, the following de-

scribed mechanism is provided. A driven shaft 62 of the main synchronizing clock 8 is journaled in the supporting bracket 38 and it is operatively associated by means of gearing 63 with a gear-wheel member 64 loosely mounted on the end of the master clock shaft 37 between the supporting bracket 38 and the member 39. The gear-wheel member 64 is provided with oppositely extending arms 65 and 66, the latter carrying a counter-balance and the former having a lateral extension 67 providing a mounting for a latch 68.

The latch 68 is so disposed that it normally engages the shoulder 59 of the arm 56, causing the contact members 45 and 46 to be in engagement, but permitting shoulder 59 of arm 56 to pass ahead in advance of latch 68 when the main synchronizing clock departs from synchronism with the master clock 36. This, however, will not occur until main synchronizing clock 8 becomes later than the master clock in time and the latch 68 is behind the shoulder 59 of arm 56. The normal engagement between the latch 68 and the shoulder 59 while the main synchronizing clock and the master clock are in synchronism may be effected by so designing the regulating coil 19 of the main synchronizing clock 8 that it rotates at a slightly higher time rate than the master clock 36.

As shown in Fig. 1, the contact member 45 is connected by a conductor 69 and a conductor 70 to the terminal 3 of the transformer 5. The contact member 46 is connected by a conductor 71 and a conductor 15 to the intermediate tap connection 6. The conductor 71 includes an actuating winding 72 for the mechanical switches 13 and 14 whereby the same may be actuated from their normal positions shown in the drawings.

When the main synchronizing clock 8 and the master clock 36 are in synchronism, the latch 68 is in engagement with the shoulder 59 of the lever 56, causing the contact member 46 to engage the contact member 45. The closed circuit thus formed extends from the terminal connection 3 of the transformer 5 through the conductors 70 and 69, co-acting contact members 45 and 46, the conductor 71, the actuating winding 72 and the conductor 15 to the intermediate tap connection 6. The effect of energizing the actuating winding 72 is to cause the closing of switch 13 and the opening of switch 14, whereby the conductor 12, of the power supply circuit 7, may be connected to the intermediate tap connection 6. Thus currents of relatively low voltage are normally supplied to the main power circuit 7, the voltage being just sufficient to cause the clock time rate of the secondary clocks 9 and the main synchronizing clock 8 to synchronize with the master clock 36.

Should, for any reason, the main synchronizing clock 8 depart from synchronism with the master clock 36, as would occur, for in-

stance, with a lowering of the voltage supply to the transformer 5, the rate of movement of the follow-up member 64 would not coincide with that of the member 39, with the result that shoulder 59 of the arm 56 would not engage the latch 68 and the pin 53, under the force of the spring 58, would cause the arm 47 to move so as to disengage the contact members 45 and 46, whereupon the actuating winding 72 of the switches 13 and 14 would become deenergized. The switch 13 then opens by gravity, disconnecting the conductor 12 from the conductor 15, while the switch 14 closes to connect the conductor 12 to the conductor 16. The closing of the switch 14 thus causes an increased voltage to be impressed on the main power circuit conductors 11 and 12 which corresponds to the full voltage of the transformer 5. The effect of the increased voltage on the actuating motors 17 of the main synchronizing clock 8 and the secondary clocks 9 is to increase the rate of operation thereof, which continues until the main synchronizing clock 8 is in synchronism with the master clock 36, and, if the original cause of the departure from synchronism has been removed, then the contact member 46 is held in engagement with the contact member 45 and currents of normal voltage are again supplied to the conductors 11 and 12 of the main power circuit 7.

Synchronism of secondary clocks with main synchronizing clock

25 My invention further embodies means, whereby the secondary clocks 9 may be brought into synchronism with the main synchronizing clock 8 upon a departure therefrom. To this end, I provide a synchronizing conductor 73 which is connected by relatively movable contact members 74 and 75 of a relay 76 to movable contact members 77 and 78 of the switches 13 and 14. The cooperating contact members 79 and 81 of the switches 13 and 14 are respectively connected to the conductors 15 and 16. The operation of the relay 76 may be controlled by means of switches 82 and 83.

50 The switch 83, which comprises movable contact members 84, 85, and 86, may be embodied in the form shown in Fig. 4, wherein the several contact members are mounted on arms 87, 88 and 89 having a common pivot rod 91 supported in the bracket 38. These arms are so disposed as to engage the peripheries of actuating cams 92, 93 and 94, respectively, which are mounted on the shaft 62.

55 The parts just described are so designed that the switch 83 operates regularly at intervals of one-half hour to effect the energization of the synchronizing conductor 73 when contacts 85 and 86 are in contacting relation, the energization period or interval continuing for ten minutes. The energization period is 60 concluded in a manner which will be de-

scribed hereinafter when contacts 84 and 85 are in contacting relation. The intervals during which the conductor 73 is energized may be represented by the distance m on the periphery of the circle 95, Fig. 6. The exact moments of effecting and concluding each interval is accurately determined, preferably by a switch, 82.

70 The switch 82 comprises movable contact members 96 and 97 which may be actuated by the main synchronizing clock 8 at one minute intervals in the same manner as the several contact members of the switch 83.

75 Referring to Fig. 1, an actuating winding 98 of the relay 76 has one terminal 99 connected through a conductor 101, which includes a resistor 102, to the conductor 70 and transformer terminal connection 3. A remaining terminal 103 of the actuating winding 98 is connected through a conductor 104, the contact members 96 and 97, a conductor 105, the contact members 85 and 86 of the switch 83, a conductor 106, and the conductor 15, to the intermediate tap connection 6. Assuming the contact members 85 and 86 just actuated into engagement, the actuating winding 98 is energized, causing the engagement of the contact members 74 and 75 and the resulting energization of the conductor 73 at a voltage depending upon whether the conductor 12 is connected to the terminal connection 4 or the intermediate tap connection 6 of the transformer 5. If the main synchronizing clock 8 and the master clock 36 are in synchronism, then the latter connection obtains.

80 The relay 76 also comprises contact members 107 and 108, the latter being mechanically connected to the contact member 75, whereby the switch 82 and contact members 85, 86 of switch 83 may be shunted following the initial operation thereof to cause the energization of the relay actuating winding 98. To this end, the contact member 107 is connected to the terminal 103 of the actuating winding 98 and the contact member 108 is connected by a conductor 109 to the conductor 15. Hence, it may be seen that the contact members 85, 86 of switch 83 now exert no control over the energizing winding 98, since the currents traverse a circuit including the conductor 109 and the contact members 107 and 108, rather than a circuit including conductor 106, the contact members 85 and 86, conductor 105, the switch 82, and the conductor 104.

85 When the conductor 73 has been thus energized for a period of ten minutes corresponding to the interval m in Fig. 6, the movable contact member 85 is actuated into engagement with the movable contact member 84 to complete a shunt circuit around the relay actuating winding 98, said shunt circuit including the conductor 104, the switch 82, the conductor 105, contacts 84 and 85 and a conductor 110, which extends from the movable

contact member 84 to the terminal 99 of the actuating winding 98. The consequent de-energization of the actuating winding 98 results in the opening of the relay 76 and the disengagement of the co-acting contact members 74, 75 and 107, 108. Contacts 84 and 85 are then opened and the movable contact members of the switch 83 are maintained out of engagement with each other until the foregoing cycle is again repeated at the end of twenty minutes.

As hereinbefore noted, each of the secondary clocks is provided with the correction coil 27 which has sufficient ampere-turns to produce a torque three to four times as great as that established by the regulating coil 19. In order that the coil 27 may be energized when it is necessary to bring one of the secondary clocks 9 in synchronism with the main synchronizing clock 8, I provide a switch 111 which is directly actuated by the secondary clock mechanism. The switch mechanism 111 comprises a pair of mechanically interlocked switch units 112 and 113.

The switch unit 112 comprises a movable arm 114 carrying contact members 115 and 116 on the respective ends thereof which coact with contact members 117 and 118, respectively. The switch unit 113 similarly comprises a movable arm 119 carrying contact members 121 and 122 which respectively engage co-acting contact members 123 and 124. The contact members 117 and 123 may be connected by a conductor 125 which extends to one terminal of the accelerating and retarding coil 27. A remaining terminal of the latter is connected by a conductor 126 to the contact members 124 and 118. The movable contact members 115 and 116 of the switch unit 112 may be connected by a conductor 127 to the conductor 73 and the movable contact members 121 and 122 of the switch unit 113 may be connected by conductor 128 to the conductor 35.

As shown in Fig. 3 of the drawing, the mechanical design of the switch units 112 and 113 as well as the actuating means therefor is similar to that of the switch 83 shown in Fig. 4, the actuating means being a series of cams 129 which are mounted on a minute shaft 131 of each secondary clock 9. The shaft 131 may be provided with a shoulder 132 adapted to cooperate with a locking pawl 133 in such manner as to prevent a reverse movement of the clock mechanism as might possibly occur when the correction coil 27 is so energized as to retard the normal movement of the secondary clock 9.

The foregoing actuating mechanism of the switch units 112 and 113 is so designed that the movable contact arms 114 and 119 thereof are retained in the position shown in Fig. 1 of the drawing for an interval of ten minutes which corresponds to the distance x on circle 134 of Fig. 6. During the succeeding ten

minutes following interval x the movable contact arms 114 and 119 are caused to assume a neutral position, wherein the several co-acting contact members are disengaged, finally to assume a position, wherein the co-acting contact members 118, 116 and 121, 123 are respectively in engagement. The latter period is represented by the distance y on the circle 134 of Fig. 6. At the expiration of the period y , the several cams 129 then cause the contact arms 114 and 119 to assume the position shown in Fig. 1 of the drawing thereby completing a cycle of three successive positions.

Assuming the switch units 112 and 113 in the position shown in Fig. 1, a circuit extends from the synchronizing conductor 73 through the conductor 127, the co-acting contact members 115 and 117, the conductor 125, the regulating coil 27, the conductor 126, the co-acting contact members 122 and 124, the conductor 128 and conductor 35 to the conductor 11, of the main power circuit 7, thus permitting currents to traverse the winding 27 so as to cause an increase in the effective flux. When the switch units 112 and 113 are actuated into a position wherein the co-acting contact members 118, 116 and 121, 123 are in engagement, currents are caused to traverse the regulating coil so as to cause a decrease in the effective flux.

As shown in Fig. 6, the operating periods x and y of the switch units 112 and 113 are so related to the energizing period m of the synchronizing conductor 73 that if the secondary clocks 9 are in synchronism with the main synchronizing clock 8, the regulating coil 27 is connected to the conductor 73 only during the period of deenergization of the conductor 73. However, should one of the secondary clocks 9 be slow with respect to the main synchronizing clock 8, then the operation period x during which the regulating coil 27 is connected to the conductor 73 overlaps the energizing period m so that the movement of said secondary clock is accelerated until it is in synchronism with the main synchronizing clock 8.

Should the secondary clock 9 be fast, then the operating period y of the switch units 112 and 113 overlaps the energization period m of the conductor 73, thereby causing a reverse energization of the regulating coil 27 and hence an opposite or retarding effect on the secondary clock mechanism. Thus it is seen that when one of the secondary clocks 9 departs from synchronism with the main synchronizing clock 8, the regulating coil 27 thereof is energized by corrective currents operating to bring the two clocks into synchronism.

Attention is directed to the fact that the corrective effect of the winding 27 of each secondary clock 9 is further increased when currents of relatively high potential are sup-

plied to the line 73 as results when a difference occurs in the rate of operation of the main synchronizing clock 8 and the master clock 36.

While I have shown only one form of embodiment of my invention, for the purpose of describing the same and illustrating its principles of construction and operation and circuit arrangement, it is apparent that various changes and modifications may be made therein without departing from the spirit of my invention, and I desire, therefore, that only such limitations shall be imposed thereon, as are indicated in the appended claims or as are demanded by the prior art.

15 I claim:

1. A clock system comprising in combination, a master clock, a synchronizing clock, a main power circuit for actuating said synchronizing clock, said main power circuit being under low tension when said clocks are in synchronism, means for impressing high tension across said main power circuit, and means including an auxiliary circuit for controlling said first mentioned means when said 20 synchronizing clock departs from synchronism with said master clock and when said synchronizing clock thereafter regains synchronism with said master clock.

2. A clock system comprising in combination, a master clock, a synchronizing clock, a main power circuit for actuating said synchronizing clock, follow-up mechanism controlled by said synchronizing clock, contacts rotatably mounted and driven by said master 35 clock and adapted to be kept closed by said follow-up mechanism when said synchronizing clock is in synchronism with said master clock, an auxiliary circuit controlled by said contacts, and a switch controlled by said auxiliary circuit for maintaining low tension across said main power circuit when said contacts are closed, and for maintaining high tension across said power circuit when said contacts are open.

45 3. A clock system comprising in combination, a synchronizing clock, a master clock controlling said synchronizing clock, a secondary clock, a main power circuit continuously actuating said synchronizing clock and said secondary clock, a secondary power circuit for said secondary clock, a source of power, and means controlled by said synchronizing clock for causing said secondary power circuit to be connected to said source 50 of power for a predetermined period of time whereby said secondary clock may receive power from both of said power circuits.

4. A clock system comprising in combination, a synchronizing clock, a secondary clock, a main power circuit for actuating said clocks, a secondary power circuit for said secondary clock, accelerating and retarding means in said secondary clock, means controlled by said secondary clock for connecting, disconnecting, and reversing the connection of said

accelerating and retarding means to said secondary power circuit.

5. A clock system comprising, in combination, a main power circuit, a clock operatively connected thereto, said clock including a unit comprising accelerating and retarding means, a secondary circuit, means for periodically energizing said secondary circuit, and means for operatively associating said unit and its accelerating and retarding means with said secondary circuit periodically for definite time intervals, said last named means including a switch for alternating the associated relation of said unit and its accelerating and retarding means with said secondary circuit.

6. A clock system comprising, in combination, a main power circuit, a secondary circuit, means for energizing said secondary circuit periodically for intervals of definite duration, a clock normally actuated by energy derived from said main power circuit, accelerating and retarding means for said clock, said accelerating and retarding means comprising a single device, and means to periodically associate said accelerating and retarding means 80 as a single device with said secondary line so as to periodically control acceleration and retardation of said clock only by electrical energy derived from said secondary line.

7. A clock system comprising, in combination, a main power circuit, a clock adapted to be advanced at a substantially uniform rate by energy derived from said main power circuit, means for affecting the rate of advancing movement of said clock, a secondary line 100 adapted to be energized periodically for definite time intervals, and pole changing means controlled by said clock for connecting said first-named means to said secondary line periodically to cause either faster or slower 105 movement of said clock.

8. A clock system comprising, in combination, a main power circuit, a secondary circuit adapted to be energized for predetermined periods, a clock connected so as to be driven continuously by energy derived from said main circuit, means capable of varying the rate of advancing movement of said clock, and pole changing means to associate said last-named means with said secondary 110 circuit whereby energy derived from said secondary circuit may cause a change in the rate of movement of said clock when said secondary circuit is energized.

9. A clock system comprising, in combination, a main power circuit, a clock, an induction disk motor therefor including a potential coil and a regulating coil deriving electrical energy from said main power circuit, a secondary circuit adapted to be periodically energized, a second regulating coil, and means for periodically connecting said second regulating coil to said secondary circuit.

10. A clock system comprising, in combination, a main power circuit, a clock, an induc-

tion disk motor therefor including a potential coil and a regulating coil continuously connected to said main power circuit, a second regulating coil for affecting the rate of advancing movement of said clock, a secondary circuit means for periodically energizing said secondary circuit, and switching means for periodically connecting, disconnecting and reversing the relation of said second regulating coil with said secondary circuit.

11. A clock system comprising, in combination, a main power circuit, a clock operatively connected thereto, said clock including a unit comprising accelerating and retarding means, a synchronizing clock, a secondary circuit, an auxiliary circuit controlled by said synchronizing clock for causing energizing of said secondary circuit periodically, and means for operatively associating said unit with said secondary circuit periodically for definite time periods, said last named means including a switch for reversing the associated relation of said unit with said secondary circuit.

12. A clock system comprising, in combination, a main power circuit, a synchronizing clock, a secondary circuit, means controlled by said synchronizing clock for energizing said secondary circuit periodically for intervals of definite duration, a clock normally actuated by energy derived by said main power circuit, accelerating and retarding means for said clock, and pole changing means controlled by said clock whereby said accelerating and retarding means are associated with said secondary circuit so as to periodically control the acceleration and retardation of said clock only by electrical energy derived from said secondary circuit.

13. A clock system comprising, in combination, a main power circuit, a clock adapted to be advanced at a substantially uniform rate by energy derived from said main power circuit, a secondary circuit, a synchronizing clock, electrically operated means for affecting the rate of advancing movement of said first named clock, means adapted to energize said secondary line periodically for definite time intervals, and pole changing means controlled by said first named clock for connecting said electrically operated means to said secondary circuit periodically to cause either faster or slower movement of said clock.

14. A clock system comprising, in combination, a main power circuit, a synchronizing clock, a secondary circuit, means controlled by said synchronizing clock for energizing said secondary circuit for predetermined periods, a clock connected so as to be driven continuously by energy derived from said main circuit, means capable of varying the rate of advance movement of said clock, and pole changing means controlled by said clock to associate said last

named means with said secondary circuit whereby energy derived from said secondary circuit may cause a change in the rate of movement of said clock when said secondary circuit is energized.

LAURENCE S. HARRISON.
